BOTTLE CONTAINER

George F. Richter, Bogota, N. J., assignor to
Scovill Manufacturing Company, Waterbury,
Conn., a corporation of Connecticut

Application February 23, 1942, Serial No. 431,903

10 Claims. (Cl. 215—12)

This invention relates to containers and particularly to a container adapted to hold a perfume bottle or the like.

One of the objects of this invention is to provide a metal container for a bottle that will serve as a protecting guard for the bottle, and at the same time may be embellished in a desirable manner to provide an attractive dress for said bottle.

Another object of this invention is to provide a container for receiving a perfume bottle or a glass vial in such a manner that in normal position the discharge end of the bottle neck will be so disposed in the container as to render it difficult to discharge the contents of the bottle, and provision being made to elevate the container to a position where the contents thereof can be readily discharged from the neck end of said bottle.

It is further a purpose of this invention to provide a stopper or closure for the bottle neck that will be of a character as to make it difficult or more or less inaccessible to remove the closure when the bottle is in normal position in the container, and which closure may be made more accessible by moving the bottle to a discharging position relative to the container.

The full nature of this invention, along with other objects and various advantages thereof, will be more apparent from a consideration of the following description when read in connection with the accompanying drawing, in which:

Fig. 1 is a perspective view of the device with the parts in their normal inoperative position.

Fig. 2 is a front elevation of the container with a portion broken away to show better the interior construction.

Fig. 3 is a vertical section through the same taken on a plane passing through the longitudinal center of Fig. 2.

Fig. 4 is a top plan view of the same, and

Fig. 5 is a transverse horizontal section of the same taken along the line 5—5 of Fig. 2, looking in the direction of the arrows.

Referring now to the drawing in which like numerals designate like parts throughout the several views, the numeral 10 indicates generally a metal container within which is confined a glass bottle or vial 12 such as is used for perfumes or like substances. The container 10 comprises essentially a body shell 14 having a closed base and an open top and which is adapted to be closed by a cover member 16. The container 10 in this instance is of a general elliptical shape in cross-section to conveniently accommodate the particular shape of bottle used, and it is to be under-

stood that the shape of the container will be more or less contingent upon the shape of the bottle which the container is to accommodate. The front and rear walls of the body shell 14 are formed outwardly with relatively broad column-like projections 18 extending the full length of the body shell 14 and conveniently provide for opposed channels 20 within the body shell 14. The face walls of the projections 18 at the upper ends are provided with cut-out sections 19 for purposes as will appear later.

As shown in the drawing the bottle in this case is provided with a stopper or closure 22 having threaded connection with the bottle neck 13. The shape of the closure 22 assumes almost a complete sphere with only the upper half portion projecting through a correspondingly shaped aperture 24 in the cover member 16. This particular shape is merely shown as an example, and it will be apparent that other shapes may be employed and designed with the idea that when the bottle is in its normal retracted position within the container, the exposed part of the bottle closure will be of a nature as to make it difficult for anyone to grasp onto or to be loosened from the container by any severe usage to which the device might be subjected in carrying it around in a handbag.

The cover member 16 is detachably secured to the body shell 14 by a snap locking engagement so that the cover may be readily removed to allow the assembly and removal of the bottle 12. To this end the cover member 16 is provided with a pair of lateral extensions 26 that serve to cover the upper open ends of the column-like projections 18. The ends of the extensions are folded over as at 28 and then extend downwardly into resilient lugs 30. The folded portions 28 engage in the cut-out sections 19 at the upper extremities of the column-like projections 18, and are designed to lie flush with the face walls of said projections 18 and serve to properly orient the cover member 16 relative to the body shell 14. The upper intermediate portions of the column-like projections 18 are formed with directly opposed inwardly projecting nubs 32 and the resilient lugs 30 are provided with complementary apertures 34 that are adapted to snap lock over the nubs. The nubs 32 are preferably made quite rounded so that, when the lugs 30 are guided downwardly over said nubs, the end of said lugs 30, in the act of assembling the cover, will be capable of camming over said nubs until the apertures 34 in the lugs 30 align therewith and snap lock thereabout. Further a similar cam action will result between

the lug apertures 34 and the nubs 32 when force is exerted on the cover member to remove the same from the body shell.

In order to further carry out the intent of this invention, the container 10 is so designed that when the bottle 12 is disposed in the normal retracted position within the container 10, the transverse end of the bottle neck 13 will lie substantially flush with the top surface of the cover member, as shown by dotted outline in Fig. 3. In this position it will be apparent that the condition is not ideal for discharging the contents of the bottle 12. Therefore, in order to elevate the bottle 12 in the container 10 so that the bottle neck 13 will project a substantial distance through the opening 24 in the cover 16 to a position to conveniently discharge the contents of the bottle 12, provision is made of the following mechanism. The bottle 12 is adapted to be elevated and retracted in the container 10 by means of a U-shaped strap member or bottle elevator 36 having two opposed leg members 38 that are fitted and guided within the channels 20. The intermediate portions of the leg members are formed with inwardly bowed sections 40 that serve to embrace the adjacent side walls of the bottle 12. The bowed sections are designed in such a manner relative to the dimensions of the bottle that, when the bottle is inserted within the container, it will be frictionally embraced by the bowed sections and further the engagement of the bottle with the bowed sections will spring the upper ends of the legs outwardly to frictionally engage against the adjacent walls of the channels 20 and which upper portions of the legs I choose to call friction pads 42. It is to be understood that the degree of bend in the bowed section is such that the bottle engaging therewith will force the friction pads 42 outwardly sufficiently to create enough friction in the channels 20 such as to hold the bottle in any elevated position.

Means are provided on the outside of the container for operating the bottle elevator 36 in the form of a thumb piece 44. The thumb piece in this case is shown as preferably made of a composition material and attached to the adjacent leg member 38 of the bottle elevator 36 by means of a tubular rivet 46 embedded in said thumb piece. The rivet 46 passes through a relatively short slot 48 provided in the face of the column-like projections 18. The rear face of the thumb piece 44 is provided with a boss 50 surrounding the tubular rivet and of a size to slidably fit in slot 48. It is to be noted that the boss and tubular rivet are located preferably adjacent the lower end of the thumb piece and the length of the thumb piece thereabove is sufficient to cover the entire length of the slot 48 so that said slot will not be exposed any time that the bottle is disposed in the container in its normal retracted position. As best shown in Figs. 4 and 5 the opposite longitudinal sides of the thumb piece are provided with integral rearwardly extending flanges 52 that embrace the opposite side walls of the front column-like projections 18, and this construction serves to prevent the thumb piece from swinging about in case the attaching rivet 46 should be loosened relative to its fixed position with the elevator leg 38.

In order to operate the device the bottle 12 is elevated by means of the thumb piece 44 to a position where more of the stopper 22 will be exposed above the cover member 16 to allow a more convenient grasp of the same for removal purposes. With the bottle 12 elevated the neck

13 will be projected above the cover to facilitate the dispensing of the bottle contents. The upward movement of the bottle carried by the elevator member 36 is controlled by the thumb piece boss 50 coming to rest against the upper end of the slot 48 as a stop. It will not be necessary for the operator to continually hold the thumb piece as the friction pads 42, as previously explained, are designed to engage in the channels with sufficient pressure to retain the bottle in such elevated position, whereupon the bottle closure may be removed and ready access had to the contents of the bottle. The operations for closing and returning the bottle to its normal position within the container will, of course, be self-evident.

While the form of the invention herewith shown and the description embraces a preferred embodiment of the same it is to be understood that the construction may be varied as to mechanical details without departing from the spirit of the invention and the scope of what is claimed.

I claim:

1. In a container for a receptacle, a casing open at one end and having a column-like projection on its outside surface presenting a face wall and a pair of parallel side walls perpendicular to said face wall with an oblong slot in said face wall, an elevator member slidably mounted in said casing, a push button disposed in front of said face wall and having a single rivet connection with said elevator member through said slot, and a pair of flanges extending rearwardly from the opposite edges of said push button adapted to slidably embrace said side walls of said projection and prevent said push button twisting relative to said casing and elevator member.

2. In a container for a receptacle having a projecting neck, a casing open at one end and having diametrically opposed column-like projections on the outside of said casing providing for longitudinal channels in the interior thereof which open through the open end of said casing, a cover member closing the casing opening and having an aperture aligned with said receptacle neck, said cover member having extensions for covering the open end of said channels, lugs depending from said extensions and projecting into said channels, and means providing for a detachable snap-locking engagement of said lugs in said channels.

3. In a container for a receptacle having a removable closure, a casing open at one end and having diametrically opposed channels in its inner walls opening through the open end of said casing, a cover member closing the casing opening and having an aperture through which the closure is adapted to project, said cover member having extensions for covering the open end of said channels, lugs depending from said extensions and projecting into said channels, and means providing for a detachable snap-locking engagement of said lug in said channels.

4. A container as defined in claim 3 wherein said snap-locking means comprises rounding nubs formed inwardly from said channels and complementary apertures provided in said cover lugs.

5. In combination, a receptacle having a reduced neck, a closure removably connected to said neck, a container for said receptacle comprising a casing having an open end and a cover having means for telescopic engagement into and detachable interlock with the open end of said casing, said cover having an opening aligned with said neck, a slide embracing said receptacle and slid-

able in said casing, said slide when retracted in said container positioning the end of said receptacle neck in a plane substantially flush with the opening in said cover, said neck closure being of a character such as to substantially close the opening in the cover and to render it more or less inaccessible when said receptacle is in a retracted position in said container and accessible when said receptacle is in an elevated position in said casing, and means connected to said slide and operable outside of said casing for moving said slide and elevating said receptacle to a position to facilitate the removal of said closure and project the neck through the cover aperture.

6. In combination, a receptacle having a reduced neck, a closure removably connected to said neck, a container for said receptacle comprising a casing shell open at one end and a cover for closing the open end of said casing shell, said cover having means for detachably interlocking engagement with the interior of said casing shell, said cover designed to be entirely removed from said casing shell and also having an aperture aligned with said neck and through which the closure partially projects when the receptacle is in retracted position in said container, an elevator member slidably mounted in said casing shell and having means for frictionally retaining said receptacle in axially adjusted position in said casing shell, and means connected to said elevator member and accessible from the outside of the casing shell for causing said elevator to be axially moved within said casing for disposing the receptacle in said container in an operable position whereby more of the closure will be exposed above the cover to facilitate removal of same and said neck will be projected through said cover aperture.

7. In combination, a receptacle having a reduced projecting neck, a closure for said neck, a casing open at one end and having opposed longitudinal channels in its inner walls, a cover detachably interlocked with the open end of said casing and having an aperture therein aligned with said neck and on a plane substantially common with the end of said neck when the receptacle is in retracted position in said casing, an elevator member in the form of a U-shaped strap having portions formed out of the legs thereof for frictionally receiving said receptacle, said elevator member slidably mounted in said casing and having its legs axially guided in said opposed channels, and means connected to said elevator and

accessible from the exterior of said casing for axially elevating and retracting said elevator member in said casing and carrying said receptacle therewith, said elevator member when elevated projecting the neck of said receptacle through said cover opening to facilitate the removal of said closure.

8. The combination of a receptacle and a casing as defined by claim 7 wherein the elevator member is provided with means to frictionally retain the receptacle in any axial position to which it may be moved within the casing.

9. In combination, a receptacle, a casing open at one end and having diametrically opposed longitudinal channels in its inner walls, a cover detachably secured to said casing and having an aperture therein aligned with said neck, an elevator member comprising a U-shaped strap the legs of which are adapted to be slidably mounted and guided in said channels, said legs having their intermediate portions bowed inwardly to frictionally engage said receptacle, the bowed portions of said legs being of a degree such that when the receptacle is assembled therebetween the upper ends of the legs will be forced outwardly into said channels to engage therein with sufficient frictional force to maintain the receptacle in any elevated position within the casing, and a push button means exterior of the casing and connected to said elevator member for moving the latter and associated receptacle to any axial position within said casing.

10. In a container for a receptacle, a casing open at one end and having diametrically opposed column-like projections on the outside of said casing providing for longitudinal channels in the interior of said casing and presenting exterior face walls flanked by a pair of parallel side walls perpendicular to said face walls on the outside of said casing, one of said projections having a longitudinal slot in the face wall thereof, a strap-like elevator member for receiving said receptacle and having leg portions guided in said channels, a push button slidable along the face wall of the projection having the slot therein and having a single rivet connection with said elevator member through said slot, and a pair of flanges extending rearwardly from the opposite edges of said push button and disposed alongside said parallel walls of said projection to prevent said push button twisting relative to said casing and elevator member.

GEORGE F. RICHTER.
